UNITED STATES PATENT OFFICE.

MARY J. M. LARKIN, OF WORCESTER, MASSACHUSETTS.

DESIGN FOR AN EDUCATIONAL DISPLAY-CARD.

6,440.

Specification for Design.

Patented Oct. 26, 1920.

Application filed May 17, 1920. Serial No. 382,172. Term of patent 14 years.

To all whom it may concern:

Be it known that I, MARY J. M. LARKIN, a citizen of the United States, residing at Worcester, in the county of Worcester and State of Massachusetts, have invented a new, original, and ornamental Design for an Educational Display-Card, of which the following is a specification, reference be-

ing had to the accompanying drawing, forming part thereof.

The figure is a plan view of an educational display card.

I claim:

The ornamental design for an educational display card, as shown.

MARY J. M. LARKIN.
